D. S. ANDREWS

SHIP LOADING AND UNLOADING SYSTEM

Filed Dec. 5, 1921

FIG. 1.

FIG. 2.

INVENTOR:

DONALD S. ANDREWS

BY

John Ernest,

ATTORNEY.

UNITED STATES PATENT OFFICE.

DONALD SHIELDS ANDREWS, OF CLEVELAND, OHIO, ASSIGNOR TO ANDREWS CRANE CORPORATION, OF CLEVELAND, OHIO. A CORPORATION OF DELAWARE.

SHIP LOADING AND UNLOADING SYSTEM.

Application filed December 5, 1921. Serial No. 519,822.

To all whom it may concern:

Be it known that I, DONALD S. ANDREWS, a citizen of the United States, resident of Cleveland, county of Cuyahoga, and State 5 of Ohio, have invented new and useful Improvements in Ship Loading and Unloading Systems, of which the following is a specification, the principle of the invention being herein explained and the best mode in 10 which I have contemplated applying that principle, so as to distinguish it from other inventions.

This invention relates to systems of loading and unloading ships and has for its object to enable freight to be rapidly transferred from a car on the pier directly to the ship or vice versa.

The accompanying drawings together with the following description set forth in 20 detail one embodiment of the invention, the disclosed means, however, constituting but one of the various mechanical forms in which the principle of the invention may be employed.

25 In the annexed drawings:

Fig. 1 is a sectional view showing, in full lines, the crane removing freight from a box car, and in dotted lines, the crane in 30 position to lower the freight into the hold of the ship.

Fig. 2 is a similar view showing the crane delivering freight into the hold of the ship.

The pier 1 has a railroad track 2, running longitudinally thereof, on which the 35 box cars 3 or other types of freight cars may be placed. The pier 1 may be covered by a shed structure 4. Alongside and parallel with the railroad tracks 2 is an overhead crane track 5 upon which is mounted the 40 crane 6 which comprises a mast 7 suspended from the power driven carriage on the track 5 and a vertically adjustable swinging boom 8. The boom 8 carries hoisting tackle 9 and the entire operation of the 45 crane is controlled from the cab 10 mounted to move with the boom. The boom is caused to enter the side door of a car or a side opening in the ship by moving the crane along the track 5 and swinging the 50 boom laterally at the same time.

The shed 4 is provided with one or more side openings 11 alongside of which a ship to be loaded or unloaded may be positioned. Projecting through the opening 11 is a 55 branch or extension track 12 connected with

the crane track 5. Outside the shed 4 the extension track 10 has a pivoted outer end portion 13 adapted to be folded up out of the way by means of hoisting tackle 14 when not in use, so as not to interfere with the movement of a ship in approaching or leaving the pier, and adapted to be lowered into operative position overhanging a ship 15 after the ship has been positioned for loading or unloading, as shown in full lines in Fig. 1.

In operation the crane 6 is brought alongside a box car, the boom 8 is projected into the doorway of the car and a package of freight is engaged by the hoisting tackle 9, 70 lifted clear of the floor, and the crane 6 is then operated to move the boom with its load laterally out of the car doorway. The crane is then moved along the track 5 to the switch section 12 adjacent the ship being 75 loaded and out upon the overhanging track 13 where it is positioned directly over the hatch of the ship. The freight is then lowered into the hold of the ship by means of the tackle 9. The operation in unloading the ship is just the reverse of that described.

As shown in Fig. 2 the crane 6 may be employed to transfer freight through a side opening 16 in the ship in the same manner 85 as through the side door of a box car.

What I claim is:

1. In a ship loading and unloading system, the combination with a pier, of an overhead track thereon having extensions adapted to project beyond the edge of the pier and overhang a ship docked at the pier, and a crane suspended on said overhead track and having a vertically movable portion and a boom on said movable portion, whereby the 90 crane may be moved into position over the ship and may be lowered into position opposite a side opening in the ship and said boom may be projected through said side opening.

2. In a ship loading and unloading system, the combination with a pier, of an overhead track thereon having extensions adapted to project beyond the edge of the pier and overhang a ship docked at the pier, and a crane suspended on said overhead track and having a vertically suspended mast 105 movable over said track and track extensions into position to overhang a ship, and a boom mounted to pivot and move vertically on 110

said mast and having tackle on its end, said mast and boom being movable into position to dispose the boom opposite a side opening in the ship and the boom with its tackle being adapted to project into said side opening of the ship for directly placing and removing freight in and from the vessel without other handling.

3. In a ship loading and unloading system, the combination with a pier having a railroad track thereon adapted to receive freight cars for transporting freight to and from a ship docked at the pier, of an overhead track arranged between the railroad track and the side of the pier, a crane carriage on the overhead track, a mast depending from the carriage, and a boom adjustably mounted on the mast for vertical and horizontal movement and having tackle thereon for engaging freight, whereby said carriage and said boom may be adjusted to overhang a ship and may be adjusted to project said boom through the side openings of the ship and a freight car on the pier to directly transfer freight between the ship and the car without intermediate handling.

4. In a ship and freight car loading and unloading system, the combination with a pier, of a railroad track for freight cars spaced from the edge of the pier at which a ship may dock and a crane mounted on the pier between the edge and the railroad track and movable to project into the freight car and into a side opening in the ship and adjustable into position to overhang the ship for directly transferring the freight between the ship and the car.

5. That method of handling freight between ship and shore, which consists in removing the freight from a box car or a ship directly by a suitable mechanism, transporting the freight by said mechanism to the box car or ship in which the freight is to be deposited, and finally projecting the same mechanism through the opening in the side of the box car or the ship to directly position the freight in its final position in the box car or in the ship.

Signed by me this 11th day of November, 1921.

DONALD SHIELDS ANDREWS.
